CREEL APPARATUS

Peter C. Pasquerello, Lanark, Pa.

Application May 10, 1943, Serial No. 486,448

10 Claims. (Cl. 242—131)

This invention relates to creels and the like, such as are used in the textile industry to support multiples of yarn supply cones which are to be unwound incident to warping or other yarn transfer operations common in the textile art; and to the individual yarn cone units of such creels.

In the art of warping, particularly as carried out by the modern shops of limited capacity, it has been the practice to employ relatively small standard spool creels of approximately four hundred and fifty spool capacity, for applying the individual yarns from these creels unto a measuring or warping reel, and from the latter directly unto a warp beam. After such shops have their equipment installed for most efficient operation, and production orders develop an unusual output demand, certain problems arise in connection with such creel arrangements. For example, to satisfy an unusual output demand, it may become necessary to increase the creel capacity. However, in the referred to shops, space limitations usually make it difficult, if not impractical, to substitute creels of larger dimensions than those already in place. Then again, a more or less general industrial increase in the demand for loaded creel spools may create supply and delivery difficulties preventing the said shops from promptly obtaining an adequate supply of spools for operating their creels as desired, or necessary, to avoid production losses, or the loss of orders which cannot be promptly satisfied.

One object of my invention is to overcome the mentioned and other difficulties, by providing novel creel equipment adapted to effect increased yarn capacity over the said standard creels without necessitating an increase in the installation space.

Another object is to provide such equipment which is more efficient in operation than the referred to standard prior art creels.

A further object is to provide such equipment having novel features of advantage over the said heretofore available creel constructions.

Another object is to provide such equipment from which the yarn can be withdrawn at a relatively higher speed, and which does not necessitate as frequent replenishment of the individual yarn sources, as the mentioned standard spool creels.

An additional object is to provide such equipment in which the yarn tension of all the yarns is alike at all times and remains uniform during the entire yarn unwinding operation.

It is also an object of my invention to provide

a novel yarn supply unit for creels and the like, which is simple in construction; adapted to take standard size yarn cones of all materials ordinarily used in warping; designed to limit or confine the ballooning of the yarn withdrawn from such a cone; which embodies yarn guide and tension means in a new and advantageous manner; and has other desirable features not present in available creel units of this general type.

With these and other objects in view, which will become more apparent from the following detailed description of certain practical and illustrative embodiments of my novel creel and yarn cone unit, shown in the accompanying drawings, the invention comprises the novel elements, features of construction and arrangement of parts in cooperative relationship, as hereinafter more specifically pointed out in the claims.

Referring to the drawings:

Figure 1 is a side elevational view of a creel embodying my invention.

Fig. 2 is a partial front elevational view of the upper end of the creel shown in Fig. 1, as seen by looking in the direction of the arrow A in said figure.

Fig. 3 is an enlarged fragmentary side elevational view of a certain creel frame element shown in Fig. 1, and two identical yarn cone units which form part of my invention.

Fig. 4 is a top plan view of Fig. 3, as seen by looking in the direction of the arrows 4—4 in said figure.

Fig. 5 is a view similar to Fig. 4, but showing a certain member of the yarn cone unit in another position.

Fig. 6 is an enlarged cross-sectional view of the yarn cone unit of my invention, taken substantially as indicated by the arrows 6—6 on Fig. 4.

Figs. 7, 8 and 9 are, respectively, rear elevation, cross-sectional and front elevational views of the upper yarn cone unit shown in Fig. 3; Figs. 7 and 8 showing the unit as seen by looking in the direction of the arrows 7—7 and 8—8 in Fig. 6.

As shown in Figs. 1 and 2, one practical creel construction of my invention comprises two vertical end frames 11 and 12, which are united by a plurality of horizontal members or boards 14, rigidly secured to the end frames in suitable manner. The end frames 11 and 12 are provided with a suitable wheel arrangement at their bottom, as indicated at 15, to facilitate movement of the creel along the floor.

The end frames 11 and 12 may be of triangular configuration as shown, or otherwise constructed

to provide, with the cross-members 14, a yarn supply mounting surface of desired area and inclination to enable the accommodation thereon of a predetermined number of yarn supply units in vertically inclined superimposed relationship assuring free and separated movement of the yarns as later described.

Side plates or brackets 18 are rigidly secured to the top board 14, across the outer upper ends of which is fixed a cross-bar 17 having a circular glass rod 18 secured to its top in such manner as to present a smooth supporting and aligning surface over which the yarns from the creel supply units may pass on their way to the usual measuring or warping reel (not shown). In order to maintain the yarns in desired spaced relationship when passing over the rod 18, a common type of reed 18^a is provided rearwardly of the rod 18, so that the individual yarns may be separated from each other by the spacing or separating elements 18^b of the reed, in accordance with well known practice. The reed 18^a is mounted on the cross-bar 17, or otherwise secured to the frame structure of the creel, to accomplish the stated purpose.

A second cross-bar 19, similar to the cross-bar 17, is mounted on the top frame member 14, at the rear and slightly below the bar 17, and this second cross-bar 19 also has a circular glass rod 19^a secured to its top to provide a resting surface for the yarns Y when in relaxed or lowered position, as indicated by the dot-and-dash line Y' at the top of Fig. 1.

The individual yarn cone units of my invention, generally indicated by the numeral 20, are secured in suitable manner to laterally inclined and uniformly spaced bars or slats 21, of wood or other material, fastened against the horizontal members 14.

As shown in Fig. 2, the units 20 are arranged in laterally staggered vertical rows to achieve minimum spacing therebetween, and to effect separation of the yarns extending from the individual units to the glass rod 18 in substantial correspondence with the spacing determined by the reed 18^a. It will also be noted from Figs. 1 and 2, that the units 20 are arranged in vertically and laterally inclined superimposed relationship in each vertically extending row, that is, each row of units is inclined rearwardly from the vertical, as shown in Fig. 1, and inclined sidewise from the vertical, as shown in Fig. 2.

As illustrated in Figs. 3 to 9 inclusive, one practical form of my novel yarn cone unit 20 comprises a plate or support 22, a cylindrical casing 23, a yarn cone mounting or pin 24, an arcuate bracket 25 having an extension 25^a, yarn guide means 26 and 27, and yarn tension means 28.

The cylindrical casing 23 and the yarn cone mounting pin 24 are fixedly secured to the support 22 in such relation that the pin 24 is centrally located within the casing. The diameter of the casing is such that all standard yarn cones of various types of materials can be accommodated therein in such manner that the inner surface of the casing is spaced from the cone a determined distance to effect desired confinement of the ballooning of the yarn when being wound from the cone.

The plate 22 is secured to the frame element 21 by wood screws 22^a which pass through apertures 22^b in said plate, as shown in Figs. 6 and 7.

The end portions 25^b and 25^c of the bracket 25 are connected with pivot pins 29 and 29^a located at diametrically opposite points at the

top and bottom of the casing 23. The pivot pin 29^a is fixed in the casing 23, while the pin 29 is loosely engaged in an aperture of the casing 23 and provided with a head at its top and bottom. This arrangement permits the intermediate part of the bracket 25, which carries the yarn guide means 26, 27, and the yarn tension means 28, to be moved or swung in a horizontal plane from the position shown in Fig. 4, to the position shown in Fig. 5.

When the bracket 25 is in the position illustrated in Fig. 4, the yarn guide means 26, 27, and the yarn tension means 28 are in active or operative position, and the bracket 25 extends vertically and centrally across the front of the casing 23. This places said yarn guide and tension means in substantial alignment with the longitudinal axis of the yarn cone mounting pin 24, as clearly illustrated in Fig. 6.

To seat a full yarn cone C on the pin 24, the bracket 25 is first swung sidewise to a position adjacent the front of the casing 23, as illustrated in Fig. 5. This leaves the front end of the casing 23 open, or unobstructed, for ready insertion or removal of a yarn cone.

The yarn tension means 28 comprises a usual arrangement of two circular discs 30 and 31 contactingly mounted on a pin 32 freely passing through central apertures in the discs. The lower end of the pin 32 is threaded and passes through a correspondingly threaded aperture centrally located in the bracket extension 25^a. To maintain the pin 32 fixed in the position shown, a lock nut 33 is applied to its lower threaded end against the underside of the bracket extension 25^a. To prevent vibration of the tension discs, a felt pad 34, or other vibration absorbing means may be interposed between the lower disc 31 and the upper surface of the bracket extension 25^a, as clearly illustrated in Fig. 6.

During unwinding of the cone C, the yarn Y passes from the cone through yarn guide 26, between the tension discs 30 and 31, through yarn guide 27, over the glass rod 18 through reed 18^a and to the measuring reel (not shown).

During such unwinding operation, ballooning of the yarn Y is limited or confined by the inner wall of casing 23, as illustrated in Fig. 6.

In order to prevent accidental movement or displacement of the bracket 25 while in the active or operative position shown in Figs. 4 and 6, the bracket is releasably held in place by detent means comprising a convex protuberance 35 on the upper bracket part 25^b, which registers with a complementary concave depression 36 in the casing 23. A compression spring 37, on the pivot pin 29, between its head and the bracket part 25^b, functions to normally maintain the detent elements in engagement. The bracket part 25^b is in limited vertical sliding engagement with the pivot pin 29, so that the application of sufficient sidewise force on the bracket 25 overcomes the downward pressure of the spring 37, will effect release of the detent means and permit free movement of the bracket 25 to its inactive position as portrayed by Fig. 5.

When the bracket 25 is moved from active to inactive position, or vice versa, the yarn guide and tension means carried thereby are moved in a horizontal or substantially equi-distant plane relative to the glass rod 18.

Although I have found in practice that such parts of the unit 20 as the support plate 22, pin 24, casing 23, bracket 25, pivot pins 29 and 29^a and tension device 28, can be made of metal to

satisfactorily provide the structural and functional advantages of my invention, it is to be understood that such parts may also be formed of plastic or other materials to impart to the unit whatever advantages may accrue from such substitution of materials. Of course, the yarn guide means 26 and 27, may be in the form of porcelain eyeclets.

The creel construction of my invention illustrated by Figs. 1 and 2, when made substantially the same in size and general configuration as the previously referred to standard form of spool creel (capacity 450 spools) used in warping shops of moderate capacity at the present time, has a yarn cone capacity of about two hundred and twenty-five cones. Since standard size yarn cones contain much more yarn than standard size yarn spools, the actual yarn capacity in weight of such a standard spool creel compared with one constructed in accordance with my invention is approximately 150 pounds as against 675 pounds, or roughly, my improved creel has about five times the yarn weight capacity of such a standard spool creel. Furthermore, it is a well known fact that the yarn unwinding speed of such a standard spool creel is limited by the practical speed of rotation of the spools. My improved creel is not subject to this limitation and it is therefore, entirely practical to attain an unwinding speed with the latter which is three or more times greater than that of such standard creels. A further comparative advantage resides in the perfectly uniform unwinding tension of the yarns from all the cone units of my improved creel construction, as compared with the varying tension of the yarns from the spools of a standard creel, which results from their varying diameter and change in rotational force required as the weight of the spools decreases. These and other comparative advantages make it possible to reduce the cost of the yarn transfer operation to approximately one-half when my improved creel is employed in place of the said standard creels.

Since the yarn cone units 20 individually embody yarn guide and tension means in combination with means for confining or limiting the ballooning of the yarn and means for accommodating standard size cones of various materials used in warping, such units are also adapted to function as complete attachments for converting the referred to standard spool creels into cone creels. This can be accomplished by removing the usual spool, yarn guide and tension means from the frames of said standard creels, mounting thereon my novel units 20, and adding a glass rod and reed or equivalent arrangement at the top, substantially as shown in Figs. 1 and 2. Besides attaining the mentioned advantages of my improved creel construction, such a change will obviously eliminate all difficulties and disadvantages characteristic of the spool creel and impart the benefits and advantages of my invention without change in the size or general configuration of the creel equipment previously utilized. The units 20 can be similarly utilized as attachments for improving other forms of yarn feeding equipment.

Of course, the creel and yarn cone unit improvements specifically described, by which I obtain the noted results, can be changed and modified in various ways without departing from the invention herein disclosed and hereinafter claimed.

I claim:

1. A yarn cone unit for a textile creel or the like, comprising a support, a yarn cone mounting on said support, a cylindrical casing mounted on said support and arranged to spacedly surround a yarn cone when seated on said mounting, a bracket on said casing arranged to be selectively moveable to a plurality of positions adjacent the front of the latter, and yarn guide means on said bracket positioned so as to be in substantial alignment with the longitudinal axis of said cone mounting when the bracket is in one of its selected positions.
2. A yarn cone unit for a textile creel or the like, comprising a support, a yarn cone mounting on said support, a cylindrical casing mounted on said support and arranged to spacedly surround a yarn cone when seated on said mounting, a bracket on said casing arranged to be selectively moveable to a plurality of positions adjacent the front of the latter, detent means for releasably holding the bracket in one of its selected positions, and yarn guide means on said bracket positioned so as to be in substantial alignment with the longitudinal axis of said cone mounting when the bracket is in one of its selected positions.
3. A yarn cone unit for a textile creel or the like, comprising a support, a yarn cone mounting on said support, a cylindrical casing mounted on said support and arranged to spacedly surround a yarn cone when seated on said mounting, a bracket on said casing arranged to be selectively moveable to a plurality of positions adjacent the front of the latter, two yarn guide elements and an intermediate yarn tension means on said bracket positioned so as to be in substantial alignment with the longitudinal axis of said cone mounting when the bracket is in one of its selected positions.
4. A yarn cone unit for a textile creel or the like, comprising a support, a yarn cone mounting on said support, a cylindrical casing mounted on said support and arranged to spacedly surround a yarn cone when seated on said mounting, an arcuate bracket on said casing arranged to be selectively moveable to a plurality of positions adjacent the front of the latter, and yarn guide means extending through said bracket at a point in substantial alignment with the longitudinal axis of said cone mounting when the bracket is in one of its selected positions.
5. A yarn cone unit for a textile creel or the like, comprising a support, a yarn cone mounting on said support, a cylindrical casing mounted on said support and arranged to spacedly surround a yarn cone when seated on said mounting, an arcuate bracket the ends of which are pivotally mounted at the top and bottom of said casing so as to permit the bracket to be selectively moved to a plurality of positions adjacent the front of the casing, detent means for releasably holding the bracket in one of its selected positions, tension means for maintaining the bracket and detent means in cooperative relationship, and yarn guide means extending through said bracket at a point in substantial alignment with the longitudinal axis of said cone mounting when the bracket is in one of its selected positions.
6. A yarn cone unit for a textile creel or the like, comprising a support, a yarn cone mounting on said support, a cylindrical casing mounted on said support and arranged to spacedly surround a yarn cone when seated on said mounting, an arcuate bracket the ends of which are

pivotably mounted at the top and bottom of said casing so as to permit selective movement of the bracket to a plurality of positions adjacent the front of the casing, detent means for releasably holding the bracket in one of its selected positions, a yarn guide aperture in said bracket in substantial alignment with the longitudinal axis of said cone mounting when the bracket is in one of its selected positions, two yarn tension discs contactingly arranged adjacent said yarn guide aperture, vibration absorbing means between one of said discs and said bracket, and a yarn guide element in substantial alignment with said yarn guide aperture at the opposite side of said tension discs.

7. A textile creel including a frame; a plurality of similar yarn cone units mounted on said frame in vertically and laterally inclined superimposed relationship, each of said units comprising a yarn cone, a cylindrical casing arranged to spacedly surround said cone, a member on said casing arranged to be selectively moveable to a plurality of positions adjacent the front of the latter, and yarn guide means on said member positioned in substantial alignment with the longitudinal axis of said cone when the member is in one of its selected positions; and a yarn guide means adjacent the top of said frame arranged to effect transverse alignment of the yarns from said units.

8. A textile creel including a frame; a plurality of similar yarn cone units mounted on said frame in vertically and laterally inclined superimposed relationship, each of said units comprising a yarn cone, a cylindrical casing arranged to spacedly surround said cone, a member on said casing arranged to be selectively moveable to a plurality of positions adjacent the front of the latter, detent means arranged to releasably maintain said member in one of its selected positions, 40

and yarn guide means on said member positioned in substantial alignment with the longitudinal axis of said cone when the member and detent are in cooperating relationship; and yarn guide means adjacent the top of said frame arranged to effect transverse alignment of the yarns from said units.

9. A textile creel including a frame; a plurality of similar yarn cone units mounted on said frame in vertically and laterally inclined superimposed relationship, each of said units comprising a yarn cone, a cylindrical casing arranged to spacedly surround said cone, a member on said casing arranged to be selectively moveable to a plurality of positions adjacent the front of the latter, and yarn guide and tension means on said member; yarn guide means adjacent the top of said frame arranged to effect transverse alignment of the yarns from said units; and a reed for the yarns from said units coextensive with and arranged in parallel relationship with said latter yarn guide means.

10. A textile creel including a frame; a plurality of similar yarn cone units mounted on said frame in vertically and laterally inclined superimposed relationship, each of said units comprising a yarn cone, a cylindrical casing arranged to spacedly surround said cone, a member on said casing arranged to be selectively moveable to a plurality of positions adjacent the front of the latter, and yarn guide means on said member positioned in substantial alignment with the longitudinal axis of said cone when the member is in one of its selected positions; yarn guide means adjacent the top of said frame to effect transverse alignment of the yarns from said units; and means arranged to alignedly support the yarns extending beyond the latter yarn guide means when said yarns are in relaxed condition.

PETER C. PASQUERELLO.
